UNITED STATES PATENT OFFICE.

HARRY E. DOERR, OF ST. LOUIS, MISSOURI, ASSIGNOR TO SCULLIN STEEL CO., OF ST. LOUIS, MISSOURI, A CORPORATION OF MISSOURI.

RAILWAY-CAR TRUCK.

1,390,344.

Specification of Letters Patent. Patented Sept. 13, 1921.

Application filed September 3, 1920. Serial No. 407,832.

To all whom it may concern:

Be it known that I, HARRY E. DOERR, a citizen of the United States, residing in the city of St. Louis and State of Missouri, have invented certain new and useful Improvements in Railway-Car Trucks, of which the following is a specification.

This invention relates to railway car trucks, and more particularly to side frames and journal boxes and an interfitting connection of same.

One object of the invention is to provide a simple and improved journal box which will function smoothly in a side frame to equalize the pressures on journal brasses.

Another object is to provide a simple and efficient connection between the side frame and journal box, especially where the tension member of the side frame has been straightened out to locate the intersection of the neutral axes of the tension and compression members outside the center of the journals.

These and other objects are accomplished by means of the arrangement disclosed on the accompanying sheet of drawings, in which—

Figure 1 is a fragmentary side elevation of a side frame and the associated journal box shown in section embodying my invention;

Fig. 2 is a fragmentary top plan view of said side frame and journal box;

Fig. 3 is an end elevation of the same;

and,

Figs. 4 and 5 are end and side views, respectively, of a shim which may be inserted between the side frame and journal box.

The various novel features of my invention will be apparent from the following description and drawings and will be particularly pointed out in the appended claims.

Referring to the figures of the drawings, it will be noted that I have shown a truck side frame 10 preferably integral in form, in which the neutral axes of the tension and compression members 11 and 12, respectively, meet at a point N outside the center of the journal 13, the same being done by maintaining the web 14 of the tension member 11 straight throughout its length up to the inner pedestal jaw 15, and then causing the same to take the form of a curve over to the other coöoperating pedestal jaw 16.

These depending pedestal jaws 15 and 16 preferably are formed integrally with the truck side frame, the upper interior surface 16' of the side frame between the jaws being curved longitudinally to receive a journal box 17, the top or upper wall of which is curved or crowned transversely with respect to the box to conform to the curved portion 16' of the side frame. The upper interior surface 18 of the journal box is varied in shape from the standard to receive the standard Master Car Builders' journal brass 19, it being noted that no wedge is provided intermediate the brass 19 and the upper interior surface of the journal box. The top of the journal box is also crowned longitudinally of the box, as shown particularly in Fig. 3, for the purpose of permitting a rocking motion of the journal box transversely with respect to the side frame 10 for equalizing the pressures on the journal brasses. However, to permit such transverse rocking movement of the journal box, the pedestal guides 20 on the journal box are separated an increased amount to provide a proper and increased clearance between said guides 20 and the pedestal jaws 15 and 16.

The pedestal jaws 15 and 16 each have spaced flanges 21 and 22 to provide vertical pockets 23 for the reception of laterally extending ears 24 on the journal box, said flanges 21 and 22 and the ears 24 having registering openings 25 and 26, respectively, for the reception of suitable fastening means, such as bolts 27, the openings 26 in the ears 24 being elongated to permit both sides of the journal box to move vertically in a guided manner within the pedestal jaws to permit the reception of shims 28, which may be of various dimensions, between the truck side frame and the top of the journal box. The shim preferably, as shown in Figs. 4 and 5, is arcuate in shape to conform to the upper transversely curved or crowned surface of the journal box and to the under curved surface 16' of the truck side frame, said shim having upstanding shoulders 29 for embracing opposite sides of the side frame.

By means of this arrangement a truck side frame and journal box and the interfitting connection therebetween are provided adapted to meet the various requirements for successful commercial use.

It is my intention to cover all modifications of the invention falling within the spirit and scope of the following claims.

I claim:

5. 1. In a railway car truck, the combination of a side frame having pedestal jaws, the upper interior surface of the side frame between the jaws being curved longitudinally, and a journal box received between said jaws having its top crowned transversely of the box to fit said curved surface and being crowned longitudinally of the box to permit rocking of the latter for equalizing pressures on the journal brasses.
10. 2. In a railway car truck, the combination of a side frame having pedestal jaws, the upper interior surface of the side frame between the jaws being curved longitudinally, and a journal box received between said jaws having its top crowned transversely of the box to fit said curved surface and being crowned longitudinally of the box to permit rocking of the latter for equalizing pressures on the journal brasses, said journal
15. 25. box having pedestal guides spaced sufficiently from said pedestal jaws to permit said rocking movement of the journal box.
3. In a railway car truck, the combination of a side frame having pedestal jaws, the upper interior surface of the side frame between the jaws being arcuate in shape to straighten out the tension member and for causing the intersection of the neutral axes of the tension and compression members to

fall outside of the center of the journals, and 35 a journal box the top of which conforms to said arcuate portion of the side frame and which also is crowned longitudinally of the box for permitting a rocking action of the latter with respect to the side frame.

4. In a railway car truck, the combination of a side frame having pedestal jaws, and a journal box received by said pedestal jaws and having a top crowned in a plurality of directions and coöperating with the side 45 frame, the crowning in one direction permitting the journal box to have a transverse rocking movement with respect to the side frame for equalizing pressures on the journal brasses.

5. In a railway car truck, the combination of a side frame having pedestal jaws, a journal box received by said pedestal jaws and having a top crowned in a plurality of directions and coöperating with the side frame, 55 the crowning in one direction permitting the journal box to have a transversely rocking movement with respect to the side frame for equalizing pressures on the journal brasses, and means whereby said journal 60 box may guidedly move in a vertical direction within said truck side frame to permit the insertion of a shim between said truck side frame and journal box.

Signed at St. Louis, Missouri, this 30th 65 day of August, 1920.

HARRY E. DOERR.
